UNITED STATES PATENT OFFICE

ALFRED E. CARLILE, OF MEADVILLE, PENNSYLVANIA

DESIGN FOR A PULL FOR A SLIDE FASTENER

Application filed February 1, 1932. Serial No. 42,687. Term of patent 7 years.

To all whom it may concern:

Be it known that I, ALFRED E. CARLILE, a citizen of the United States, residing at Meadville, in the county of Crawford and State of Pennsylvania, have invented a new, original, and ornamental Design for a Pull for a Slide Fastener, of which the following is a specification, reference being had to the accompanying drawing, forming a part thereof.

In the drawing:

Fig. 1 is a plan view of the pull for a slide fastener showing my new design;

Fig. 2 is a side view of the same pull.

I claim:

The ornamental design for a pull for a slide fastener substantially as shown.

In testimony whereof I affix my signature.

ALFRED E. CARLILE.
